SPRAY DAMPENER FOR LITHOGRAPHIC OFFSET PRESSES

Horace Edwin Marsden, London, England

Application February 18, 1946, Serial No. 648,275
In Great Britain February 26, 1945

3 Claims. (Cl. 101—147)

1

The present invention relates to devices for dampening the surface of the printing plates employed in lithographic offset printing presses and has for its object to provide modified and improved apparatus for effecting the desired dampening operation without contact between the printing surface and a solid carrier for the dampening liquid, in the manner described and claimed in parent British patent specification No. 574,595 of Aug. 25, 1946, and in the corresponding U. S. Patent No. 2,448,226 of Aug. 31, 1948.

With that object in view the fluid pressure atomising nozzles adapted to direct sprays of finely atomised liquid in the form of a mist onto the surface of the printing plate, are mounted in a consolidated structure upon a block shaped member hereinafter referred to as manifold block in which the manifolds, i. e. the main passages supplying separately the dampening liquid, usually water under pressure, and the pressure fluid, usually consisting of compressed air, are integrally embodied together with other necessary parts of the device as hereinafter more fully described.

Accordingly, the invention consists in having the manifolds for the supply of the pressure gas and liquid under pressure respectively to the passages feeding the spray nozzles, as well as the valves controlling said feed arranged to operate within the manifold block with which the spray nozzles proper are consolidated to form a substantially integral unit.

A practical form of construction of the invention is illustrated in the accompanying drawings in which Fig. 1 represents a full cross-section of the consolidated dampening unit and Fig. 2 is a plan view thereof.

The main components of the spray unit as here illustrated as well as the controlling and actuating mechanism are substantially as described in the parent U. S. and British patents referred to above. The atomising device proper comprises as in the parent case, a series of compressed spray nozzles G, each consisting of an outer or air diffusing collar 42 and an inner or water nozzle 41, with its flared terminal 47, their respective passages 46, 46a, converging to a common mixing chamber 47a. These nozzles are arranged to extend in a longitudinal plane so as to project towards the printing plate surface carried by the cylinder 11 without, however, contacting the latter. By preference as shown, they are mounted upon or substantially arranged within flanged adaptors 40a, which, in their turn, are mounted upon a block shaped member 10a herein referred to as the manifold block. This block may be cast, cut from the solid or built up from suitable sections if desired to form a box-like structure which is preferably rectangular in cross section as shown and of sufficient length to extend across

2

the entire width of the printing plate carried by the cylinder 11.

The block 10a is adapted to be suitably supported between the frame members 10 of the press so that its external, preferably plain, longitudinal face, i. e. the face provided to carry the adaptors 40a of the spray nozzles G lies parallel to the printing plate surface. These nozzles are preferably equally spaced and may be arranged in a straight line as shown in Fig. 2 or in a plurality of rows banked one above the other.

As in the parent U. S. and British patents, the water and air feed passages of these spray nozzles G are supplied from the main ducts or manifolds 33 and 32 which in the present construction are embodied in the manifold block 10a so as to extend longitudinally therein substantially one above the other as shown or in any desired position. The ducts leading transversely from these manifolds to connect the latter with the nozzle feeding passages, are governed by spring influenced adjustable valves, i. e. valve 53 controlling the flow of compressed air from the manifold 32 to passages 45 and 46 via an air chamber 44 and a needle valve 48 controlling the flow of water under pressure to the flaring terminal 47 of the water nozzle through a water chamber 40 provided in the adaptor 40a. The stems of these valves 48 and 53 are tightly packed by glands which have their main body portions located within the manifold block 10a.

Again as in the parent U. S. and British patents, the spray from the nozzle G is enclosed in a spray guard S in the form of a box-like structure interposed between the spray nozzles and the printing plate cylinder 11 so as to extend across the entire width of the latter but in the present arrangement shown, it is constructed to house the whole atomising structure and part of the manifold block 10a to which it is detachably secured in any desired manner. The bottom 71 is fitted with a gutter 105 suitably connected to a drainpipe while the top of the guard is formed with an inset glass panel 72 through which the condition of the sprays can be readily inspected. Adjustable side shields 73 adapted to close selected portions of the open side of the spray guard S are secured in place by set screws 74 which are screwed into the top front edge of the guard analogous to the construction in the parent case.

The operating mechanism for each compound spray unit G comprises a rocking lever 58 pivoted at 58a in a bracket 58b which is secured to the rear face of the manifold block 10a as shown by screws or in any other suitable manner. At its upper end each lever 58 carries a valve operating lever proper 59 secured to the front face of which is a plate 60 adapted to engage collars on the valve spindles 48 and 53 and to actuate these valves when the lever 58 is rocked. The levers 58 are rocked simultaneously through a control shaft 62 extending parallel to the manifolds 32

and 33 and carrying cams 61 secured to the shaft by set screws set to engage adjustable cam followers 63 secured to the lower extremities of the levers 58. This extremity of each lever is formed as an angle bracket into which a threaded spindle of the cam follower 63 is screwed and the further end of the cam follower spindle carries a serrated wheel 64 which is engaged by a spring loaded plunger pin 65 so that the cam follower spindle can readily be rotated to adjust the throw of the lever. The cam shaft 62 is rotated by a handle 66 and carries a pointer 68 to indicate the setting of the device on an indicator scale 67, all of these parts of the operating and setting mechanism being substantially as described in the parent U. S. and British patents. The cam shaft 62 carrying the cams 61 is journalled in swinging-bearing brackets 75 which are pivotally mounted upon a transverse shaft 16a fixed in and extending between side frames 10b. Working in conjunction with the bearing brackets 65 is a throw-off cam 80 situated on the inside face of the frame 10b and adapted to rock on shaft 81 on which it is set through an extension piece 82 so as to be rocked from an "on" position in contact with a shoulder 75a on the swinging bracket to an "off" position controlled by a stop pin 84 secured to the frame 10b. This shaft 81 is controlled by a hand lever 83 and the bracket 75 is held in position under tension by springs 88. The operation and its control are again substantially as described in the parent U. S. and British patents. A description in greater detail does not therefore appear to be required since it does not form any actual part of the main characteristic feature of this invention.

It will be appreciated by those skilled in the art that by the consolidation of the parts of the mechanism as herein described and illustrated, not only is a great deal of labour saved by the material reduction of actual components and means for their assembly but more especially by the embodiment of the fluid passages and manifolds within the manifold block most of the packing means for rendering the device water- and air-tight hitherto necessary have been dispensed with, whereby the manufacture is simplified and its precision is greatly enhanced.

I claim:

1. In a lithographic offset printing press having a printing cylinder and a printing plate carried thereby, a dampening device for spraying atomized water directly onto the printing plate carried by the printing cylinder, comprising in combination a block shaped member extending across the entire width of said printing plate, a first manifold embodied lengthwise within said block shaped member for supplying air under pressure, a second manifold embodied lengthwise in this said block shaped member parallel with said first manifold for the supply of water under pressure, a series of compound air and water spray jets fed from said manifolds for spraying atomized water onto said printing plate, a series of adapters for securing said compound spray jets integrally to said block shaped member, valves operating within said block shaped member regulating the supply of air and water from such manifolds to said spray jets and cam actuated means carried by said block shaped member for mechanically controlling said valves for regulating the supply of air and water under pressure to said spray jets substantially as set forth.

2. In a lithographic offset printing press having a printing cylinder and a printing plate carried thereby, a dampening device for spraying atomized water directly onto the printing plate carried by the printing cylinder, comprising in combination a block shaped member extending across the entire width of said printing plate, a first manifold embodied lengthwise within said block shaped member for supplying air under pressure, a second manifold embodied lengthwise in said block shaped member parallel with said first manifold for the supply of water under pressure, a series of compound air and water spray jets fed from said manifolds for supplying atomized water to said printing plate, a series of adaptors for securing said compound spray jets integrally to said block shaped member, valves operating within said block shaped member regulating the supply of air and water from such manifolds to the spray jets and cam actuated means carried by said block shaped member and operable for mechanically controlling pre-selectable valves for regulating the supply of air and water under pressure to a predetermined number 10 of said spray jets for the dampening of a pre-selected portion of the printing plate substantially as set forth.

3. In a lithographic offset printing press having a printing cylinder and a printing plate carried thereby, a dampening device for spraying atomized water directly onto the printing plate carried by the printing cylinder, comprising in combination a block shaped member extending across the entire width of said printing plate, a first manifold embodied lengthwise within said block shaped member for supplying air under pressure, a second manifold embodied lengthwise in same said block shaped member parallel with said first manifold for the supply of water under pressure, a series of compound air and water spray jets fed from said manifolds for supplying atomized water to said printing plate, series of adaptors for securing said compound spray jets integrally to said block shaped member, valves operating within said block shaped member regulating the supply of air and water from such manifolds to said spray jets and cam actuated means comprising a series of rocking levers carried by said block shaped member in engagement 30 with the spindles of said regulating valves, a cam shaft carrying a corresponding series of cams, cam followers on said rocking levers and adjusting means associated with said cam followers for throwing pre-selected ones of said cam followers 35 in and out of engagement with said cams according to the area of opening in the spray guard adjusted for dampening of a pre-selected portion 40 of the printing plate substantially as set forth.

60 HORACE EDWIN MARDEN.
